THOMAS L. BURK, OF GREENSBURG, INDIANA.

Letters Patent No. 80,131, dated July 21, 1868.

IMPROVEMENT IN FENCE.

The Schedule referred to in these Letters Patent and making part of the same.

TO ALL WHOM IT MAY CONCERN:

Be it known that I, THOMAS L. BURK, of Greensburg, in the county of Decatur, and in the State of Indiana, have invented certain new and useful Improvements in Fences; and do hereby declare that the following is a full, clear, and exact description thereof, reference being made to the accompanying drawings, and to the letters of reference marked thereon.

In the annexed drawings, forming part of this specification—

Figure 1 represents a side view of the fence.

Figure 2 is a top view of the same.

The nature of my invention consists in the construction of posts A A, with two of the corners bevelled or hewed off to the centre on one side, as shown in fig. 2, for the purpose of nailing the boards on the same, so as to construct a crooked or worm-fence, making it strong and self-supporting.

By this plan the posts can always be placed plumb on a hill-side, and the ends of the boards fitted accordingly. These posts A A are fastened to a block of wood or stone, B B, in the ground, by means of a pin, C, either of wood or iron, to be fastened at the foot of the post by one or two staples or pins, D, either with small heads, or bent out at the top, so that the staple at the upper end will not let it pass out below, as shown in fig. 2. This is to anchor either a portable or a stationary fence, by making a hole in a block of wood or stone sufficient to receive the lower end of the pin C and be tight.

By this mode of fastening, the posts A A are above ground, well anchored, and cannot rot, and, together with its being a crooked fence, fortifies it against heavy storms.

The posts A A may also be fastened in the wooden or stone blocks B B, by the use of a straight round or square pin driven into the foot of the post, and then into a hole bored in the anchor-block.

The fence is greatly strengthened by the double lock or mule-lock, which is formed by passing a rail, E, from one panel to another, and splicing or letting the ends lap on each other where they rest on the boards of each panel at the middle. These rails E are locked by nailing strips F F on the panels, one on each side of the rail E and panel, always putting the strip F on the side of the rail nearest to the post, and also by a small notch cut on one side of the rail to fit one of the strips at each panel completing the lock, as shown in fig. 2. By the use of this rail E and two strips F F across each panel, one post can be saved, and each panel made sixteen to eighteen feet long.

The wire G is fastened at the top of each panel, at its centre, by passing it through a hole and lapping it around one-half of the board at the top, continuing it from one panel to the next through the whole length of the fence. This arrangement not only prevents stock from jumping over the fence, but also gives additional strength to the same.

Having thus fully described my invention, what I claim as new, and desire to secure by Letters Patent, is—

The arrangement of the notched rails E, strips F, bevelled posts A, and wire G, all constructed, arranged, and operating substantially as and for the purposes set forth.

In testimony that I claim the foregoing, I have hereunto set my hand, this 8th day of April, 1868.

THOMAS L. BURK.
